Attorney.

UNITED STATES PATENT OFFICE.

GEORGE W. CALEF, OF BOSTON, MASSACHUSETTS.

GAS-BURNER.

1,351,715.

Specification of Letters Patent. Patented Aug. 31, 1920.

Application filed November 5, 1919. Serial No. 335,821.

To all whom it may concern:

Be it known that I, GEORGE W. CALEF, a citizen of the United States, and a resident of the city of Boston, in the county of Suffolk and Commonwealth of Massachusetts, have invented certain new and useful Improvements in Gas-Burners, of which the following is a full, clear, and exact specification.

10 This invention has for its object the construction of a comparatively inexpensive, efficient and easily adjusted gas burner for use in the fire pots of kitchen ranges and the like.

15 In carrying my invention into effect, I provide a hollow member or header with means for supplying it with a mixture of burning gas and air, having a plurality of perforated tubes projecting from the header to 20 act as the burners proper, and adapt each tube for being closed at will in order to restrict the number of flame-emitting tubes to two or even one.

25 In the drawings forming part of this specification, Figure 1 is a side sectional elevation of a gas burner embodying my improvements. Fig. 2 is a cross section of the same on the line 1-1 in Fig. 1. Fig. 3 is a cross section on the line 2-2 in Fig. 1. 30 Fig. 4 is a longitudinal section of the gas-and-air supplying means.

The header consists of a metal box 3 having an open side closed by a cover 4 confined thereto by suitable means, as stove bolts. 35 This box and cover are preferably formed by casting, and has the inner surface of its side 6 provided with several bosses 7, preferably four in number. A hole is made through each boss and these holes are suitably tapped for the air-tight admission of the threaded ends of tubes 9, 10 and 11. The tube 11 is located close to the top of the header, and is provided with a row of burner holes 12 along the top-most line of its periphery, as shown in Fig. 2.

40 Lower down but spaced from each other are two other tubes 10 parallel with the first and of substantially the same length, each tube 10 having two rows of holes 13 and 50 14 along its outermost section.

In line with each tube 10, 11 within the header, is a slidabie stem 16 passing through a suitable packing 17 to the exterior of the header-cover 4. The outer end of each stem 55 16 is preferably bent upward through a guide-slot 19, and its inner end is provided

with a cap 20 faced with a layer of yielding material, preferably asbestos 21.

The burning gas is supplied through a tube 22 into a passage 23 into which it draws a certain quantity of air through the air holes 24, the mixture passing on through a tube 25 into the header, taking in with it an added proportion of air through the air holes 26. From the header the thoroughly oxygenized gas passes to the tube 10, 11 which may happen to be open, and being ignited at the holes 12, 13 and 14, it burns with a remarkably perfect combustion and with great heat.

If but comparatively little heat is desired in the stove, and that immediately beneath its top, both caps 20 controlling the tubes 10 are moved into engagement with the open ends of the latter, and, the gas being thereby shut off therefrom, the flames will issue 75 from the top tube 11 alone.

Should a maximum supply of heat be desired, all three of the tubes 10, 11 are opened by the withdrawal of their caps 20, and all emit flames.

80 Ordinarily a kitchen range is provided with a water-front for heating the water in a boiler, and opposite thereto is a partition separating the fire pot from the oven. As indicated in Fig. 2, the flames issuing from the holes 13, 14 will meet squarely against the sides of the fire pot, one of which sides will be the oven-partition and the other will be the water-front. If it is desired to heat the oven without heating the water in the 85 boiler, the tube 10 at the water-front side will be closed by its cap 20 and the opposite tube only, or the latter and the tube 11, will be permitted to supply heat.

90 Or, if hot water is wished without heating the oven, then the other tube 10 will be closed and the former closed one will be opened.

95 By entirely closing both tubes 10, and sliding the cap 20 of the tube 11 almost into contact with the latter, just enough gas can be supplied to the tube 11 to maintain a minimum amount of warmth to the stove.

100 In this way, a burner is provided which is capable of adjustment through a wide range of heat-units, and also for supplying heat to any special portion of the stove exclusively.

110 The burner should be arranged in the fire pot with the cover adjacent the stove door in order to permit of convenient access to the stems 16.

What I claim is:

1. A gas burner comprising a hollow header adapted to receive a supply of burning gas, burner tubes communicating with the interior of the header, the end of each tube within the header lying in a plane at right angles to the axis of the tube, and a disk-cap for each tube-end faced with a yielding material and having a stem in line with the axis of its associated tube, the said stems projecting through the opposite wall of the header and slidably gas-tight therein; whereby whenever the disk-caps are adjusted into contact with the tube-ends the pressure of the gas within the header aids in binding them gas-tight against the same.
2. A gas burner comprising a hollow header adapted to receive a supply of burning gas, a plurality of burner tubes communicating with the interior of the header, a cap for the inner end of each tube, a stem supporting each cap slidably supported by a wall of the header and extended through the same to the exterior thereof, each stem having means for rendering its passage to the exterior gas-tight, the outer end of each

stem being bent upward, and a slotted guide slidably receiving each upward-bend.

3. A gas burner comprising a header having means for supplying it with a burning gas, and three burner tubes projecting from and communicating with the interior of said header, the tubes being parallel, one thereof being near the top of the header and the other two being lower down and laterally spaced, the latter tubes having each two rows of jet-holes along its outermost periphery.

4. A gas burner comprising a hollow header having means for supplying it with a burning gas, and three burner tubes projecting from and communicating with the interior thereof, the tubes being parallel, one thereof being near the top of the header and having jet-holes along its topmost surface, and the other two being lower down and laterally spaced and having laterally disposed jet-holes.

In testimony that I claim the foregoing invention, I have hereunto set my hand this first day of November, 1919.

GEORGE W. CALEF.
